MANIFOLD STACK

Ruggero Luzzatto, Genoa, Italy

Application June 26, 1931, Serial No. 547,075
In Italy July 3, 1930

10 Claims. (Cl. 282—27)

The present invention relates to improvements in manifold packs provided with writing sheets which have copying means therebetween, the sheets so arranged being assembled together along 5 at least one edge so as to form a composite whole.

The novel characteristics of the invention consist in the fact that the external sides of the pack present one or more zones of writing which alternate with one or more non-writing zones, that 10 signs are provided whereby it is possible to distinguish the writing zones from the non-writing ones, that each writing zone of an external side of the pack corresponds to and is coextensive with a non-writing zone of the other external 15 side of the pack, that reproducing means are provided, between the writing sheets, which have the form of the writing zones and are arranged in co-operating position with the respective writing zones of the external sides of the pack, that is to say, in such a manner that the writings 20 or impressions effected upon any one of the writing zones may be transferred on to the corresponding zone of the underlying sheet or sheets.

The mentioned means for the reproduction of 25 the writings or signs may consist of transfer sheets having a peculiar formation, i. e., having on one side transverse zones of copying material which alternate with zones or areas clear of copying material, and having transverse zones of copying 30 material on the other side, the copying material on one side covering spaces that are coextensive with the transverse zones of blank paper on the other side.

The copying material, instead of being located 35 upon a special transfer sheet, may be disposed also at alternating zones upon the inner sides of the same writing sheets, in a manner similar to that here indicated for the case where a special transfer sheet may be used, that is to say, in such 40 a manner that there may correspond zones of copying material of equal dimensions with the writing zones of the external sides, adapted to reproduce the writings upon the corresponding zones of the underlying sheet or sheets.

45 In any case, the zones of copying material are in the same direction of the writing zones provided upon the external sides of the end sheets of the pack.

50 The writing spaces and the zones of copying material may be more or less extended; thus, they may cover one or more writing lines.

The connection of the sheets may, in particular, be effected strongly all around (along all the edges 55 of the pack) in such a manner as to render impossible a direct writing on the inner sides of

the pack without leaving noticeable trace thereof. In this manner, if the pack is handed on to a person, an office, etc., closed and intact, it provides the guarantee that the various copies of the writings are absolutely identical with each other, which copies can be obtained by dissociating the pack in any manner whatever such as, for instance, by removing the edge that keeps the various sheets assembled together, and thus separating the various sheets constituting the 10 pack, the said sheets present writing upon both sides. This may be particularly useful for supplying the persons sending correspondence by post with an authenticated copy of the correspondence 15 itself without the post office having to compare the copies with each other.

The invention also includes the feature that the form of the sheets may be such that, once the pack is disassembled in any manner such as, for instances, by removal of the border holding the various sheets together, all the sheets, or some of them, present the form of postal letter cards, and are provided with means whereby all or some of the sheets thus obtained may be closed upon themselves, the said means consisting, in particular, in a preliminary folding and in a gummed edge provided with perforations. This gummed edge serves as in the common postal letter card, for the closing of each postal letter card on itself, after having been folded along the above 25 mentioned folding line, while the said perforations will help later by tearing away the edge of the closed postal letter card to open them. Besides these lines of perforation of each postal letter card, there may also be provided on the pack, 30 as will be seen from the description of the drawing, additional exterior lines of perforation, which will facilitate the detachment of the outer edge of the pack, along which (exterior edge) the sheets are joined together all around, and so to 35 separate the sheets. To render more secure the fixing of the sheets, along the said edge, besides using the usual adhesive material, further union means can be applied, as for instance four metallic eyelets, one at each side. The above mentioned 40 means for effecting the writing upon the two sides of the pack and thereby upon the two sides of each sheet constituting the said pack, make it possible for each postal letter card to bear upon one side the address and upon the other side 45 the correspondence.

In the annexed drawing there are illustrated by way of example two practical embodiments of the present invention. Fig. 1 shows in open position the double frame or folder to contain the several sheets of the manifold pack; Fig. 2 shows 50

the interior of said frame with the two end sheets of the pack secured in place; Fig. 3 shows in perspective, and partly open, a manifold pack consisting of three sheets of writing paper separated by two carbon paper sheets; Fig. 4 shows in transverse section a complete pack closed; Fig. 5 shows a face of a particular type of carbon paper intended to be used for the reproduction of the writing performed on one exterior face 10 of the pack as well as on the other exterior face thereof; Fig. 6 shows a manifold pack made according to the invention, wherein the sheets have the form of postal letter cards after the pack has been dissociated by removal of the edges.

15 Throughout the views, the same references indicate the same or corresponding parts.

Referring to the embodiment illustrated in Figs. 1 to 4, 1 designates a double frame or folder. 2 and 3 represent the two outer sheets of the 20 manifold pack which are pasted to the inner face of the frame as shown in Fig. 2; the whole is folded along the line 4—4, and between the outer sheets 2 and 3 there is located a third sheet of writing paper 5 interposed between two sheets 25 of carbon paper 6 and 7. All the sheets 2, 3, 5, 6 and 7 are of the same dimensions with the folder and sheets assembled, the assemblage of such sheets and of the folder, arranged in the manner described, constitutes the pack which is completed by gumming together the mutually facing marginal strips 8 of the frame, which are thus brought together in actual contact.

The pack thus contrived is passed through a perforating device which makes lines of perforations 9 along which the marginal portion of the pack may be torn away to free the three copies.

Each copying sheet has on each face zones *a* of copying material alternating with zones *b* without copying material, each zone provided 40 with copying material on one face corresponding to and being coextensive with a zone without copying material of the other face. Fig. 5 shows a face of the copying sheets 6 and 7 with the copying zones *a* and the non-copying zones *b*. On 45 the exterior faces of the external sheets 2 and 3 are provided (Fig. 3) white zones 13 upon which it is intended to be written and obscure zones 14, upon which it is not intended to be written, each writing zone 13 of one exterior face of the pack 50 corresponding and being co-extensive with a non-writing zone 14 of the other exterior face of the pack.

To each writing zone of the exterior faces correspond as to form and position a copying zone 55 of the sheet 6 and a copying zone of the sheet 7, said zones of copying material being in operative position with regard to the corresponding writing zone in such a way that the writings effected upon any one of the writing zones are reproduced on 60 the corresponding or similarly disposed inner faces of the other writing sheets without resulting superposition of writings or mirror writings. In this manner, after the pack has been dissociated, the sheets 2, 3 and 5 will, as a result, have 65 written matter on the two faces, and the original writings will appear on the two exterior faces of the pack, while the indirect-writings will appear on the inner faces of the sheets 2 and 3 and on both faces of the intermediate sheet 5.

70 Fig. 6 shows the front face of a manifold pack, the sheets of which, after the dissociation of the pack itself, present the form of postal letter cards. The zones designated by 13a, 13b, 13°, 13', and 13'' are zones upon which writing may be effected; more particularly, 13a denotes the zone

wherein the clerk of the sending postal office will put the indication of the office from which the registered letter is sent forward, and 13b the zone in which he will insert his signature and the posting date; in 13° the sender will have written his name and surname, and in 13' his address, while in 13'' the sender himself will have put the address of the destinee, that is to say, his name, surname, city and street or square. In contrast therewith, 14 denotes zones upon which no writing or impression must be made. To the zones 13a, 13b, 13°, 13' and 13'' of the front side of the pack, side visible in Fig. 6, have accurately corresponding zones located upon the rear face of the pack (the face that is not seen in the figure), 15 and upon which no writing or impression has to be effected. Upon the rear side of the pack and upon zones which correspond identically in form and arrangement with the zones 14 of the side that is viewed in Fig. 6, the sender will write the 20 correspondence; all that is effected on the pack before the closing border holding the sheets all around has been taken away. The safety eyelet-holes 12 are designed to effect the firm closure 25 of the pack.

Said eyelets consist of small metallic tubes found on the market, sometimes referred to as grommets, and serve to fix a group of sheets or the like together. In the edge indicated at 15 four holes of convenient size are made, and four 30 eyelets or small metallic tubes are introduced into said holes and then pressed or riveted over by an appropriate tool such as a pair of pincers or a machine, so that they will hold the sheets together 35 and better secure the union of said sheets along the edge 15.

Obviously, the distribution and breadth of the writing areas and the respective indications could be made different from the ones illustrated.

The carbon paper sheet to be used in connection with the pack of Fig. 6 is similar to that illustrated in Fig. 5, except for the differences depending upon the breadth and form of the writing and non-writing zones. The pack is dissociated by removal of the strips 15, and in consequence of this dissociation two or more postal letter cards are obtained which present all around a gummed edge that, for the postal letter card that is visible in Fig. 6, is indicated by 16 and included between the lines 9 and 17, such gumming portion resulting upon the face that is not seen in the figure. This gummed edge serves, as in the common postal letter cards, for the closure of the latter upon themselves, while the preliminary folding line 18, 50 18 (Fig. 6) serves merely to facilitate effecting the closure. The actual utilization of the two postal letter cards has, of course, already been 55 described above in the specification.

It is to be understood that changes may be 60 made in the formation and in the combination and arrangement of the several parts, provided such changes come within the scope of the appended claims.

Having now particularly described and ascertained the nature of the present invention and in what manner the same is to be performed, I declare that what I claim is:

1. In combination, a manifold pack comprising a plurality of opaque record sheets and a copying 70 sheet, the copying sheet having transverse zones of carbon-copying material on one side with transverse zones of clean paper therebetween and having transverse zones of carbon-copying material on the other side, the carbon-copying 75

- material on one side covering spaces that are coextensive with the transverse zones of clean paper on the other side.
2. The combination of two opaque writing sheets and a transfer sheet therebetween, said transfer sheet having spaced transverse zones of transfer material upon opposite faces thereof, the zones upon the obverse face being respectively aligned with the spaces between the zones on the reverse face.
3. In combination, a manifold pack including a plurality of writing sheets connected together at least along one edge, copying means interposed between the said sheets, the copying means consisting of a first series constituted by zones of copying material which alternate with zones clear of copying material and are disposed in operative position relatively to one of the sheets between which they are interposed and a second series, comprising zones of copying material which alternate with zones free of copying material and are disposed in operative position relatively to the other of the sheets between which they are interposed, the copying zones of one series covering spaces that are coextensive with the spaces free from copying material of the other series.
4. In combination, a manifold pack comprising a plurality of opaque sheets and at least one copying sheet, the copying sheet in each case having transverse zones of copying material on one side with transverse zones of clean paper therebetween and having transverse zones of copying material on the other side, the copying material on one side covering spaces that are coextensive with the transverse zones of clean paper on the other side.
5. In combination, a manifold pack comprising a plurality of opaque writing sheets united at least along one of their edges, and spaced zones of copying material arranged upon the interior sides of the same writing sheets, the zones of copying material of one side being respectively aligned in coextensive manner with the intermediate spaces clear of copying material of the side making contact therewith.
6. In combination, a manifold pack comprising a plurality of writing sheets assembled together, copying means interposed between said writing sheets, the copying means consisting of a first series constituted by one or more zones of copying material which alternate with one or more zones clear of copying material and are disposed in operative position relatively to one of the sheets between which they are interposed, and a second series constituted by one or more zones of copying material which alternate with zones clear of copying material and are disposed in operative position relatively to the other of the sheets between which they are interposed, the copying zones of each series covering spaces that are coextensive with the spaces clear of copying material of the other series, indicia applied upon both the external sides of the pack for the purpose of distinguishing the writing zones, in correspondence with the inner copying means, and means firmly joining the edge portions all around the writing sheets and the reproducing means to prevent any direct writing occurring on the inner sides thereof without leaving noticeable trace thereof.
7. In combination, a manifold pack comprising a plurality of writing sheets joined together, copying means interposed between the sheets, the copying means consisting of a first series of zones of copying material alternating with zones clear of copying material and in assembled condition disposed in operative position relatively to one of the sheets between which they are interposed, and a second series of zones of copying material alternating with zones free from copying material and in assembled condition disposed in operative position relatively to the other of the sheets between which they are interposed, the copying zones of one series covering spaces that are coextensive with the spaces clear of copying material of the other series, indicia applied upon both the exterior sides of the pack for the purpose of distinguishing the writing zones in correspondence with the inner copying means, means firmly joining the edge portions all around the writing sheets and the reproducing means to prevent the direct writing on the inner sides thereof without leaving noticeable trace thereof, the writing sheets presenting, in addition to the exterior edge portions adapted for the assemblage of all the sheets in a pack, also a gummed inner border formed with perforations and a line of preliminary folding for doubling each sheet upon itself to form a post letter card.
8. A manifold pack according to claim 3, wherein indicia are applied upon both the exterior sides of the pack for the purpose of distinguishing the writing zones, in correspondence with the interior copying means.
9. A manifold pack according to claim 4, wherein indicia are applied upon both the exterior sides of the pack for the purpose of distinguishing the writing zones, in correspondence with the inner copying means.
10. A manifold pack according to claim 5, wherein indicia are applied upon both the exterior sides of the pack for the purpose of distinguishing the writing zones in perfect correspondence with the inner copying means.

RUGGERO LUZZATTO.
